UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

BUTTONHOLE-SEWING MACHINE.

1,326,666.

Specification of Letters Patent. Patented Dec. 30, 1919.

Application filed January 2, 1915. Serial No. 24.

To all whom it may concern:

Be it known that I, JOHN KIEWICZ, a citizen of the United States, residing at Boston, county of Suffolk, State of Massachusetts, have invented an Improvement in Button-hole-Sewing Machines, of which the following description, in connection with the accompanying drawing, is a specification, like characters on the drawing representing like parts.

This invention relates to buttonhole sewing machines of that type which embody an under thread mechanism capable of bodily turning movement to provide for stitching around the ends of a buttonhole, and the invention has for its object to provide a novel construction by which the so-called "purl" portion of the buttonhole stitching may be formed on the top, instead of on the bottom, of the work. In stitching a buttonhole with a two-thread buttonhole sewing machine the upper and under thread are intertwined or interlaced along two separate lines, one line of interlacing coming on the upper or exposed face of the material at a distance back from the edge of the material equal to the length of the depth stitch, and the other line of interlacing or so-called "purl" usually being situated at the edge of the buttonhole slit in the material, only at the under side of the material. There are some classes of work in which it is desirable to have the "purl", or interlacing of the upper and under threads that is situated at the edge of the buttonhole, appear on the top or exposed face of the material rather than on the under side thereof, and this can be accomplished by increasing the tension on the under thread so that it will be considerably greater than the tension applied to the upper thread. Such heavy tension on the under thread, however, interferes with the operation of shifting the material at the completion of one buttonhole to bring it into position to have the next buttonhole stitched therein, owing to the fact that this shifting movement necessitates drawing out a length of the under thread to which the heavy tension is applied, and unless this is very carefully done, the under thread is likely to be broken due to the heavy tension thereon. I have by my invention provided means whereby the tension on the under thread may be relieved automatically at the end of the stitching operation on a buttonhole, said

tension being again automatically applied to the under thread when the stitching operation begins on the next buttonhole, so that during the stitching operation the appropriate heavy tension may be given to the under thread to bring the purl on the upper face of the fabric and yet when the stitching operation is completed and the work is to be shifted, the tension is released, so that the operator can bring the work into a new position without danger of breaking the under thread. My invention is adaptable for use in connection with any buttonhole sewing machine in which the under thread mechanism has a bodily turning movement to permit it to stitch around the ends of the buttonhole, whether the turning movement be a continuous one or be a vibratory one. I have, however, herein chosen to illustrate my invention as it would be applied to a sewing machine of the so-called "Reece" type, examples of which are found in the following United States patents:

No. 655,637, August 7, 1900;

No. 684,046, October 8, 1901;

No. 713,764, November 18, 1902;

and in the drawings I have shown a sufficient portion of the sewing machine such as illustrated in said patents with my improvements applied thereto to give an understanding of the invention.

In the drawings, Figure 1 is a side view partly in section of the front portion of a buttonhole sewing machine of the "Reece" type;

Fig. 2 is a section on the line $x-x$, Fig. 1;

Fig. 3 is a section on substantially the line $y-y$, Fig. 2, looking upwardly;

Fig. 4 is a section on the line $a-a$, Fig. 2;

Fig. 5 is a section on substantially the broken line $b-b$, Fig. 4.

Fig. 6 is a fragmentary perspective view of one edge of a buttonhole showing the usual concatenation of the threads forming the stitches;

Fig. 7 is a similar view showing the stitch which is formed by my improved device.

I have shown at 1 the base frame of a sewing machine on which is mounted a clamp frame 2 carrying clamp plates 3 and work-clamping members 4, these work-clamping members 4 being pivotally mounted on arms 5 which in turn are pivoted at 6 to the clamp frame. 7 indicates a portion of the

so-called stitch frame which carries both the upper and under thread mechanism. The upper thread mechanism is shown in the form of an eye-pointed needle 8 sustained 5 in a reciprocating needle bar 9 operating in ways in the head 10 of the stitch frame. The under thread mechanism is carried by a so-called stitch block 11 which is rotatably mounted in bearings 12 and 13 carried by 10 the bracket or portion 14 of the stitch frame that depends below the clamp frame. This under thread mechanism comprises a needle and looper and other operative parts, such, for instance, as are illustrated and described 15 in the above-mentioned patents, and as the present invention does not relate to the particular construction of the under thread mechanism I have not deemed it necessary to further illustrate or describe it herein. 20 Both the upper and under thread mechanism are capable of bodily turning movement about a vertical axis to permit the stitching around the ends of a buttonhole, all as set forth in said above-mentioned patents, and 25 this turning movement is effected by means of two segment gears 140 and 15 mounted on a shaft 160 and meshing with gears 17 and 48 associated with the upper and under thread mechanism, respectively. The tension 30 on the upper thread 16 is governed by a suitable tension device 170 of any appropriate construction. The tension on the lower thread 18 is controlled by a tension device 19 of any suitable construction carried by the stitch block 11 of the under 35 thread mechanism. The under thread passes up through the hollow spindle 20 of the under thread mechanism and emerges from an aperture 21, thence passes around 40 a guide pin 22 and through the tension device 19 and from thence to the needle and other operating parts of the under stitch forming mechanism, all as usual in devices of this nature. The tension device 19 thus 45 acts on the portion of the under thread between the axial thread passage through the hollow spindle 20 and the needle.

In the operation of a buttonhole sewing machine of this type it is usual to have the 50 tension on the upper thread slightly greater than that on the under thread, and when this condition exists the so-called "purl" of the buttonhole will be formed on the underside of the material at the edge of the slit, 55 as shown in Fig. 6, wherein the upper thread 16 which is carried through the material back from the edge of the buttonhole is interlaced with the lower thread 18 which passes up through the slit at points 23, the 60 latter constituting the so-called "purl" of the buttonhole. In some classes of work it is desirable that this purl or points where the two threads interlace should appear on the top edge of the fabric, and this end can 65 be accomplished by making the tension on

the lower thread 18 greater than that on the upper thread, such increased tension causing the points 23 of the interlacing to be drawn around through the buttonhole so that they appear on the top edge thereof, as shown 70 in Fig. 7. However, as stated above, there are disadvantages which arise when the under thread is subject continuously to a heavy tension because the severe tension on the under thread interferes with the rapid 75 shifting of the material at the completion of a buttonhole into a position for stitching the next buttonhole. This is because when the material is thus shifted it is necessary to draw out a length of the upper and under thread equal to the distance between the buttonholes, and where the under thread is subjected to a heavy tension, this operation is likely to cause breakage of the under 80 thread unless extreme care is used. I have 85 provided herein means for relieving the tension on the under thread automatically when the stitching operation on one buttonhole is completed, and for automatically applying the tension to the under thread when the 90 stitching on the next succeeding buttonhole is begun. This permits the under thread to be drawn out freely as the material is shifted to place it in position to have a 95 fresh buttonhole stitched.

While any suitable means for thus relieving automatically and reestablishing again the tension on the under thread may be employed, I have herein illustrated a device which operates in connection with the 100 work clamp so that the operation of clamping the work in position causes the tension on the under thread to be applied, while the operation of unclamping the work causes the tension to be released. It is not 105 essential to the invention, however, that this relieving of the tension and applying it again should be done in conjunction with the clamping and unclamping of the work. The arms 5 carrying the work clamps 4 are 110 provided with the usual forwardly-extending portions 25 provided with hooks 26 at their forward ends which embrace a lip 27 carried by a swinging yoke-shaped member 29 that is pivoted to the clamp frame 2 at 115 30. This yoke-shaped member 29 is provided with a depending portion 31 to which is pivoted at 32 an elbow-lever 33, one arm of this lever being pivotally connected at 34 to an arm 35 on a clamp-operating lever 36 that in turn is pivoted at 37 to the clamp frame 2. The arm 35 and the lever 33 constitute a toggle joint which when straightened operates through the extension 31 to swing the frame or yoke-shaped member 29 120 downwardly, the latter operating through the lip 27 and hook-shaped portion 26 to swing the clamp-carrying arms 5 downwardly, thus bring the clamps 4 against the 125 work. The lever 36 constitutes means by 130

which the clamps 4 may be brought into operative position by hand. The clamps are automatically operated by means of a lever, one end of which is shown at 38 and 5 which is actuated by a cam, all as illustrated in Patent No. 713,764. The clamp is automatically released at the end of the stitching operation by breaking the toggle lever 33, 35, as also described in said patent. This clamp-operating means forms no part of my present invention and, therefore, need not be further described as any further desirable description will be found in said prior patents.

15 In the present embodiment of my invention I propose to utilize this movement of the frame or yoke-shaped member 29 to release and apply the tension on the under thread.

20 The tension device 19 for the under thread is of the familiar type comprising two disks 40 and 41 between which the thread is confined, the disk 41 being yieldingly held in frictional engagement with the thread by a spring 42, the tension of which is regulated by the adjusting nut 43. In the illustrated embodiment of my invention the tension on the under thread is released by a tension-releasing device in the form of a pin 44 which extends through the hub 45 of the gear 48, said hub, it being noted, having a length sufficient to extend up through the bearing 12 and being secured to the stitch block 11 by means of a pin 46 which extends through the hub into the stitch block. This tension-releasing pin 44 is bent laterally at its upper end, as shown at 49, and then upwardly, as shown at 50; the upper end being tapered or wedge-shaped and in position to enter between the tension disks 40, 41 on the side thereof at which the under thread 18 enters and leaves the tension member.

This tension-releasing pin extends through the gear 48 and terminates below the gear. With this construction it will be noted that the raising of the pin 44 will force the disks 40, 41 apart, thus relieving the tension on the under thread, while when the pin occupies the position shown in Figs. 2 and 5 the under thread will be subjected to the full tension. For thus raising the pin 44 to relieve the tension, I have provided a member 51 in the form of an arm or lever which is pivoted at one end, as at 52, to the portion 14 of the stitch frame, and at the other end is provided with an eye 54 through which extends a rod 55 that is secured at its upper end to one of the arms 29. As herein shown this rod 55 has a nut or collar 56 on its lower end against which the eye 54 of the arm 51 rests, and at its upper end it extends through an ear or arm 58 secured to the member 29 and is provided with a head 57 which rests on this

ear or arm. 59 is a spring which encircles the rod and yieldingly holds the member 51 against the nut 56. The member 51 is provided intermediate of its ends with the pin-engaging portion 60 which partially encircles the usual sleeve nut 61 that is screwed on the stem 62 of the stitch block 11 and which holds the gear 48 in position, as seen in Fig. 5, this nut 61 being commonly used in this type of sewing machine. The pin-engaging portion 60 is situated directly beneath the pin 44 and is concentric with the axis about which the under thread mechanism rotates, so that as the under thread mechanism rotates the pin 44 will move around directly over said portion 60. With this construction it will be observed that when the arms 29 are raised the member 51 will be turned about its pivot and the pin-engaging portion 60 thereof will raise the pin 44 thereby to release the tension on the under thread.

In the operation of the sewing machine the act of clamping the work in position causes the frame 29 to swing downwardly about its pivot, this downward movement swinging the member 51 downwardly out of engagement with the pin 44 whereby said pin is rendered inoperative and the under thread 18 is subjected to the full tension applied to it by the tension device 19. After the work is thus clamped the stitching operation is automatically carried on, all as described in the above-mentioned patents, and during this operation the upper and under thread mechanisms are given a rotary or turning movement about their vertical axes to carry the stitching around the ends of the buttonhole. When the stitching operation is completed the work clamp is automatically released, all as described in the above-mentioned patents, and when this occurs the releasing of the clamp causes the frame 29 to move upwardly into the position shown in Fig. 1. This upward movement of the part 29 carries the member 51 upwardly, thus bringing the pin-engaging portion 60 into engagement with the tension-releasing pin 44 and elevating the latter thereby to force it between the disks 40 and 41 of the tension device and crowd them apart. This results in removing the tension on the lower thread so that it can be drawn out readily without undue strain. The tension will be held released until the work is clamped again ready for stitching the next buttonhole when the operation of clamping the work will cause the tension to be applied.

It will be noted that the under thread mechanism rotates or turns about a vertical axis and that the releasing pin 44 has a bodily movement with it. The shape and construction of the pin-engaging portion 60 of the arm 51 is such as to permit this turning movement of the under thread mecha-

nism without interfering with the operation of the machine, for so long as the pin is over any part of the curved pin-engaging portion 60 the raising of the member 51 will 5 release the tension.

In sewing machines of the type herein illustrated, the stitch frame 7 and clamp frame 2 are so positioned relative to each other when the machine is at rest that the 10 work retained in the work clamp will be in position to have the buttonhole cut, and when the machine is started, said frames have first a relative movement to bring them from buttonhole-cutting to stitching position. 15 When the parts have been moved into stitching position, the stitching operation begins and the stitch frame and clamp frame have a continued relative movement as the 20 stitches are formed down one side of the buttonhole and then back along the other side of the buttonhole. When the stitching on the buttonhole is completed, the stitching mechanism is brought to rest and said stitch frame and clamp frame have still a further 25 relative movement to carry the parts from stitching to buttonhole cutting position.

It will be noted that the tension-releasing device herein shown is connected both to the portion 14 of the stitch frame and to the 30 portion 29 of the clamp frame, and these two parts 29 and 14 have a relative movement during the stitching of the buttonhole, as above set forth. The construction of the under thread releasing device, however, is 35 such that it does not interfere with such relative movement and such that this relative movement between the parts 29 and 14 does not affect the operation thereof. The member 51 which is connected to the stitch 40 frame at 52 is pivotally connected to the rod 55, and this rod is loosely hung from the ear 58 secured to the clamp frame. Therefore, the connection between the rod 55 and the member 51 and clamp frame is sufficiently flexible to permit of any relative forward and backward movement between the 45 stitch frame and clamp frame without binding or cramping the parts.

It will thus be seen that I have provided 50 a two-thread buttonhole sewing machine in which the under thread mechanism is mounted to turn bodily about an axis perpendicular to the work with means for automatically relieving the tension on the under 55 thread at the end of the stitching operation and for automatically applying the tension to the thread at the beginning of the next stitching operation, and while I have herein shown one particular embodiment of my invention and such embodiment as applied to a sewing machine of the "Recco" type, yet I desire to state that the invention is not confined to the constructional details shown, nor is it confined in its application to the par-

ticular type of sewing machine herein illustrated. 65

I claim:

1. In a buttonhole sewing machine, the combination with upper thread mechanism, of under thread mechanism mounted for 70 bodily turning movement to provide for stitching around the end of a buttonhole, a tension device for the under thread mounted for bodily turning movement therewith, and means for automatically actuating said tension device thereby to release the tension on the under thread at the end of the stitching operation. 75

2. In a buttonhole sewing machine, the combination with an upper thread mechanism, of under thread mechanism mounted for bodily turning movement to provide for stitching around the end of a buttonhole, a tension device for the under thread 80 mounted for bodily turning movement with the under thread mechanism, and means to actuate the tension device automatically thereby to release the tension on the under thread at the end of the stitching operation. 85

3. In a buttonhole sewing machine, the combination with upper thread mechanism, of under thread mechanism including a stitch block mounted for turning movement and carrying stitch-forming instrumentalities, a tension device for the under thread 90 carried by the stitch block, and means for automatically actuating said tension device thereby to release the tension on the under thread at the end of the stitching operation. 95

4. In a buttonhole sewing machine, the combination with upper thread mechanism, of under thread mechanism mounted for bodily turning movement and provided with a needle and an axial thread passage for the under thread and means operating automatically to apply tension to the portion of the under thread between said axial thread passage and the needle at the beginning of the stitching operation on a buttonhole and to release the tension on the under thread 100 at the end of said stitching operation. 105

5. In a buttonhole sewing machine, the combination with upper thread mechanism, of under thread mechanism mounted for bodily turning movement, means partaking 110 of the bodily turning movement of said under thread mechanism to apply tension to the under thread, and means for automatically rendering the tension device inoperative upon the completion of stitching 115 operations on a buttonhole. 120

6. In a buttonhole sewing machine, the combination with upper thread mechanism, of under thread mechanism including a stitch block mounted for turning movement 125 and carrying stitch-forming instrumentalities, automatically-operative means carried by said stitch block for applying tension to

- the under thread, and means for automatically rendering said tension means inoperative upon the completion of the stitching operations on a buttonhole.
- 5 7. In a buttonhole sewing machine, the combination with work-holding means, of upper thread mechanism, under thread mechanism mounted for bodily turning movement about an axis perpendicular to the plane of the work, a tension device for the under thread mounted to partake of the bodily turning movement of the under thread mechanism, and means to render said tension device inoperative upon completion of the stitching operation.
- 10 8. In a buttonhole sewing machine, the combination with work-holding means, of upper thread mechanism, under thread mechanism mounted for bodily turning movement about an axis perpendicular to the plane of the work, a tension device for the under thread mounted for bodily turning movement with the under thread mechanism, and means to render said tension device inoperative upon completion of the stitching operation and for permitting said tension device to become operative again upon the beginning of the next stitching operation.
- 15 9. In a buttonhole sewing machine, the combination with work-holding means, of upper thread mechanism, under thread mechanism mounted for bodily turning movement about an axis perpendicular to the plane of the work, said under thread mechanism being provided with a needle and an axial thread passage for the under thread, a tension device situated to apply tension to the portion of the thread between said axial passage and the needle, and means to release the tension on the thread upon the completion of the stitching operation on a buttonhole.
- 20 10. In a buttonhole stitching machine, the combination with work-holding means, of upper thread mechanism, under thread mechanism mounted for bodily turning movement about an axis perpendicular to the plane of the work, a tension device for the under thread carried by said under thread mechanism and partaking of the bodily turning movement thereof, and means for actuating said tension device thereby to release the tension on the under thread at the completion of the stitching operation on a buttonhole.
- 25 11. In a buttonhole sewing machine, the combination with upper thread mechanism, of under thread mechanism mounted for bodily turning movement to provide for stitching around the end of a buttonhole, and means mounted for bodily turning movement with said under thread mechanism to apply an increased tension to the

under thread at the beginning of the stitching operation.

12. In a buttonhole sewing machine, the combination with work-clamping means including a clamping member movable to clamp and unclamp the work, of upper thread mechanism, under thread mechanism, a tension device for the under thread, and means actuated by the movement of the clamping member when the work is unclamped to release the tension on the under thread.

13. In a buttonhole sewing machine, the combination with work-clamping means, comprising a clamping member movable to clamp and unclamp the work, of upper thread mechanism under thread mechanism, and means rendered operative by the work-clamping movement of the clamping member to apply tension to the under thread and by the unclamping movement of said member to release the tension on the under thread.

14. In a buttonhole sewing machine, the combination with work-clamping means including a clamping member movable to clamp and unclamp the work, of upper thread mechanism, under thread mechanism, a tension device for the under thread carried by the under thread mechanism, and means actuated by the unclamping movement of said clamping member to release the tension on the under thread.

15. In a buttonhole sewing machine, the combination with work-clamping means comprising a clamping member movable to clamp and unclamp the work, of upper thread mechanism, under thread mechanism mounted for bodily turning movement, a tension device carried by the under thread mechanism, and means actuated by the unclamping movement of the clamping member to release the tension on the under thread.

16. In a buttonhole sewing machine, the combination with a clamp frame carrying work-clamping means, of a stitch frame, upper thread mechanism and under thread mechanism carried by the stitch frame, said under thread mechanism having a bodily turning movement in the stitch frame and said stitch frame and clamp frame being movable relative to each other, a tension device for the under thread movable with the stitch frame, and means actuated by the work-clamping means to render said tension device inoperative upon the completion of the stitching operation.

17. In a buttonhole sewing machine, the combination with a stitch frame, of under thread mechanism carried thereby which is mounted thereon for bodily turning movement to provide for stitching around the end of the buttonhole, a tension device for the

under thread partaking of said bodily turning movement, and means for automatically relieving the tension at the end of the stitching operation.

5 18. In a buttonhole sewing machine, the combination with an upper thread mechanism and an under thread mechanism mounted for bodily turning movement about a vertical axis, of work-clamping means, 10 and means situated beneath the work-clamping means and rendered operative by the clamping movement thereof, to apply tension to the under thread.

15 19. In a buttonhole sewing machine, the combination with under thread mechanism mounted for bodily turning movement about an axis perpendicular to the plane of the work, of a tension device for the under thread mounted for bodily turning movement with the under thread mechanism, 20 and means to render said tension device inoperative upon completion of the stitching operation and for permitting said tension device to become operative again upon the 25 beginning of the next stitching operation.

30 20. In a buttonhole sewing machine, the combination with an upper thread mechanism and an under thread mechanism, of work-clamping means constructed to hold the work clamped against movement relative thereto during the stitching of a buttonhole and comprising a movable work-clamping member, a tension device for the under thread situated beneath the work-clamping means, and means actuated by the unclamping movement of the clamping member to release the tension on the under thread.

35 21. In a buttonhole sewing machine, the combination with an upper thread mechanism and an under thread mechanism, of work-clamping means constructed to hold the work clamped against movement relative thereto during the stitching of a buttonhole and comprising a movable work-clamping member, automatically-operative means to apply tension to the under thread, and means actuated by the unclamping movement of the clamping member to render 40 said tension-applying means inoperative.

45 22. In a buttonhole sewing machine, the combination with an upper thread mechanism, and an under thread mechanism, of work-clamping means constructed to hold the work clamped against movement relative thereto during the stitching of a buttonhole and comprising a movable clamping member, and means rendered operative by 50 the clamping movement of the clamping member to apply tension to the under thread and by the unclamping movement of said clamping member to relieve said tension.

55 23. In a buttonhole sewing machine, the

combination with a stitch frame of under thread mechanism carried thereby, a tension device for the under thread, a clamp frame, work-clamping means carried thereby, said frames having a movement relative to each other during the stitching operation on a buttonhole and a further movement relative to each other at the completion of the stitching operation to relatively move said frames from stitching to buttonhole-cutting position, and means actuated by the work-clamping means when the work is unclamped for automatically releasing the tension on the under thread at the end of the stitching operation and before the completion of such relative movement of the frames.

60 24. In a buttonhole sewing machine, the combination with a stitch frame of under thread mechanism mounted thereon for bodily turning movement, a tension device for the under thread, a clamp frame, work-clamping means carried thereby, said frames having a movement relative to each other during the stitching operation on a buttonhole and a further movement after the completion of a stitching operation to relatively move said frames from stitching to buttonhole-cutting position, and means actuated by the work-clamping means when the work is unclamped for automatically releasing 65 the tension on the under thread at the end of the stitching operation and before said frames complete their relative movement.

70 25. In a buttonhole sewing machine, the combination with work-clamping means 100 constructed to hold the work clamped against movement relative thereto during the stitching of a buttonhole and comprising a movable clamping member which is brought into clamping position at the beginning of a stitching operation and is maintained in clamping position continuously during the stitching operation, of upper thread mechanism, under thread mechanism, a tension device for the under thread 105 situated beneath the clamping member, and means actuated by the clamping member to release the tension on the under thread at the end of a stitching operation.

75 26. In a buttonhole sewing machine, the combination with upper thread mechanism, of under thread mechanism mounted for bodily turning movement about a vertical axis to provide for stitching around the end of a buttonhole, said under thread mechanism being provided with a needle and an axial thread passage for the under thread, work-clamping means, a tension device for the under thread situated beneath the work-clamping means and adapted to act on the 110 under thread between said axial passage and the needle, and means for automatically actuating the tension device to release the tension on the under thread at the end of the stitching operation.

27. In a buttonhole sewing machine, the combination with work-clamping means, of upper thread mechanism, under thread mechanism mounted for bodily turning movement about a vertical axis and provided with a needle and an axial thread passage for the under thread, means situated beneath the work-clamping means and operating automatically to apply tension to the portion of the under thread extending between said axial passage and the needle at the beginning of the stitching operation on a buttonhole and to release said tension at the end of said stitching operation.

28. A buttonhole sewing machine, having in combination, stitch-forming mechanism comprising upper and under thread mecha-

nisms, a work clamp, a rotary turret carrying the under thread mechanism, mechanism for relatively actuating the stitch forming mechanism and clamp to sew about a buttonhole, an under thread tension device mounted on the turret, and mechanism for automatically actuating the tension device to apply the tension at the beginning of the sewing and to relieve the tension at the completion of the sewing.

In testimony whereof, I have signed my name to this specification, in the presence of two subscribing witnesses.

JOHN KIEWICZ.
